UNITED STATES PATENT OFFICE.

LEWIS B. WHITE, OF NEW YORK, N. Y., ASSIGNOR TO LEON ABBETT, OF JERSEY CITY, NEW JERSEY.

HYDROCARBON-BURNER.

SPECIFICATION forming part of Letters Patent No. 353,105, dated November 23, 1886.

Application filed July 10, 1885. Serial No. 171,261. (No model.)

To all whom it may concern:

Be it known that I, LEWIS B. WHITE, of the city, county, and State of New York, have invented a new and Improved Hydrocarbon-Burner, of which the following is a full, clear, and exact description.

This invention relates to that class of hydrocarbon-burners used in burning crude petroleum and other hydrocarbons as fuel, especially for steam-boilers.

The object of my invention is to avoid undue overheating of parts of the burner, thereby preventing leakage and loss of material when the heated parts contract.

15 The invention consists in the construction of parts and details, and combinations of the same, as will be fully set forth hereinafter.

Reference is to be had to the accompanying drawing, forming part of this specification, 20 in which the figure is a longitudinal sectional view of a boiler provided with my improved hydrocarbon-burner.

The boiler A is provided with a fire chamber or box, B, from which the flues or water tubes extend upward in the usual manner. 25 From the top of a closed tank or retort, C, a pipe, D, having a valve, D', extends downward into the fire-chamber B, and terminates in a flowing nozzle or spout, E. The bottom 30 of the tank or retort C is tapered, and provided with an outlet-pipe, F, having a cock, F', and below the pipe F a tank, G, is placed, from the bottom of which an outlet-pipe, H, 35 projects, which has a cock, H', and terminates in a nozzle, H''. The tank or retort C is surrounded by a closed steam-box, J, connected with the boiler A by a pipe, K, having a cock, K'. The tank or retort C has a gage-tube, L. The pipe M, provided with the 40 valve M', is connected with the tank or retort C, and serves to conduct the crude petroleum or other hydrocarbon to be used as fuel from a tank or pump into the retort. The pipe N conducts steam to the nozzle H''. 45

O is a pressure-gage connected with the retort C, and P is a pressure-gage connected with the box J.

Q is a pressure-valve in the pipe D, and is

connected by a rod, Q', with the arm R' of a cock, R, in the pipe M.

The operation is as follows: The steam in the box J evaporates the hydrocarbon in the retort C and converts it into gas, which passes through the pipe D to the nozzle E in the fire-box, and is ignited. In case the gas is not consumed as rapidly as it is produced, the pressure of gas in the retort C increases considerably, and is sufficient to raise the valve Q, whereby the valve R is opened. The gas-pressure forces some of the hydrocarbon in the tank C out through the pipe M, thus leaving more space for the gas and causing a decrease of pressure. The residuum from the hydrocarbon collects in the lower part of the retort C, and is drawn off into the tank or vessel G at suitable intervals. The cock H' in the pipe H and the cock N' in the pipe N are opened. The steam issuing from the end of the pipe N acts the same as the steam in an ejector or jet-pump, and converts the residuum issuing from the pipe H into spray, which can be burned and consumed under the boiler A or under any other boiler. For example, the residuum may be used to produce steam in the boiler A. The steam produced in said boiler is used to produce gas, and the gas, which is not used, as the residuum gives sufficient heat to produce the steam, is stored in a suitable gas-tank or gasometer for future use.

The gas need not necessarily be used in boilers, but may be used for various different purposes. In place of using steam, hot air, hot oil, or hot water may be used for evaporating the oil.

If desired, the retort may be used with a steam-coil in it.

Having thus described my invention, what I claim as new, and desire to secure by Letters Patent, is—

1. The combination, with a boiler, of a steam jacket or box connected with the same, a retort in the same, a tank, and steam-jet apparatus for converting the residuum from the retort into spray, substantially as herein shown and described.

2. The combination, with a steam-boiler, of a steam jacket or box connected with the same, a retort in the jacket, a pipe extending from the retort to the fire-box of the boiler, a pipe for withdrawing the residuum from the retort, a tank for receiving the residuum, a pipe connected with the residuum-tank, and having a nozzle in its end, and a steam-pipe extending to the nozzle on the residuum-pipe, substantially as herein shown and described. 10
LEWIS B. WHITE.
